Filed July 28, 1971, Ser. No. 167,083

Term of patent 14 years

Int. Cl. D15—99

U.S. Cl. D8—44

FIG. 1 is a front elevation of a poultry house traction cable clamp embodying my new design.

FIG. 2 is a plan view of the poultry house traction cable clamp of FIG. 1.

FIG. 3 is a rear elevation of the poultry house traction cable clamp shown in FIG. 1 and FIG. 2.

FIG. 4 is a side elevation of the poultry house traction clamp shown in FIG. 1, FIG. 2, and FIG. 3.

The broken line disclosure of a traction cable is for illustrative purposes only.

I claim:

The ornamental design for a poultry house traction cable clamp, as shown and described.
